CLAIM

The ornamental design for a shoe, as shown and described.

DESCRIPTION

FIG. 1 is a top, front, right perspective view of a shoe showing my new design;

FIG. 2 is a top, right perspective view thereof;

FIG. 3 is a top, left perspective view thereof;

FIG. 4 is a top, front perspective view thereof;

FIG. 5 is a top, rear perspective view thereof;

FIG. 6 is a top plan view thereof; and,

FIG. 7 is a bottom plan view thereof.

The broken lines shown in the drawings represent stitching
and form part of the claimed design.

The dot-dashed lines in the drawings represent the boundary
of the claimed design.

1 Claim, 7 Drawing Sheets
